(57) **CLAIM**

The ornamental design for a double-head landscape path light, as shown and described.

DESCRIPTION

FIG. 1 is a front, left and top perspective view of a double-head landscape path light showing my new design; FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof, shown enlarged in scale; and,

FIG. 8 is a bottom plan view thereof, shown enlarged in scale.

The broken lines in the drawings depict portions of the double-head landscape path light that form no part of the claimed design.
